US0D1103089S

(12) **United States Design Patent** (10) **Patent No.:** **US D1,103,089 S**
(45) **Date of Patent:** **** Nov. 25, 2025**

(54) **CHARGING PILE**

(71) Applicant: **DARWIN PRECISIONS CORPORATION**, Hsinchu County (TW)

(72) Inventor: **Yu tsung Su**, Hsinchu County (TW)

(73) Assignee: **DARWIN PRECISIONS CORPORATION**, Hsinchu County (TW)

(**) Term: **15 Years**

(21) Appl. No.: **29/969,533**

(22) Filed: **Oct. 23, 2024**

(30) **Foreign Application Priority Data**

Apr. 30, 2024 (TW) 113301987

(51) **LOC (15) Cl.** **13-02**

(52) **U.S. Cl.**

USPC **D13/107**

Primary Examiner — Barbara Fox
Assistant Examiner — Lorna M Georges

(57) **CLAIM**

The ornamental design for a charging pile as shown and described.

DESCRIPTION

FIG. 1 is a front and top perspective view of a charging pile, showing my new design;

FIG. 2 is a rear and top perspective view thereof;

FIG. 3 is a front elevation view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of the encircled portion 9 in FIG. 1.

The broken lines depict portions of the charging pile in which the design is embodied that form no part of the claimed design. The dot-dash broken lines represent boundaries of the enlarged portions and form no part of the claimed design.

1 Claim, 9 Drawing Sheets
